UNITED STATES PATENT OFFICE.

MARTIN ROBINSON, OF CAMPBELL HILL, ILLINOIS.

WATER-HEATER.

1,246,161.

Specification of Letters Patent. Patented Nov. 13, 1917.

Application filed March 24, 1917. Serial No. 157,219.

To all whom it may concern:

Be it known that I, MARTIN ROBINSON, a citizen of the United States, residing at Campbell Hill, in the county of Jackson 5 and State of Illinois, have invented certain new and useful Improvements in Water-Heaters, of which the following is a specification, reference being had to the accompanying drawings.

10 This invention relates to certain improvements in water heaters and has relation more particularly to a device of this general character especially designed and adapted for use in canning; and it is an object of 15 the invention to provide a device of this general character having novel and improved means whereby the water may be readily and conveniently heated.

It is also an object of the invention to 20 provide a device of this general character with a supplemental container or reservoir whereby heated water can be delivered within the main container as the requirements of practice may necessitate.

25 The invention consists in the details of construction and in the combination and arrangement of the several parts of my improved heater whereby certain important advantages are attained and the device is 30 rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein

40 Figure 1 is a view in elevation of a water heater constructed in accordance with an embodiment of my invention;

Fig. 2 is a sectional view taken substantially on the line 2—2 of Fig. 1;

45 Fig. 3 is a sectional view taken substantially on the line 3—3 of Fig. 1;

Fig. 4 is a longitudinal vertical sectional view taken through the device as herein embodied; and

50 Fig. 5 is a view in bottom plan of my water heater as herein set forth.

As disclosed in the accompanying drawings, C denotes a container of predetermined configuration and dimensions and 55 which has its top face open. L denotes a lid or cover adapted to close the top or

open face of the container C and provided with a hand grasp 1 whereby the lid or cover L may be readily and conveniently removed or replaced.

60

Depending from the bottom of the container C are two series of substantially triangularly arranged hollow extensions 2. The extensions of each series are separated one from the other and are preferably three 65 in number. The bottom of the container C is provided with a plurality of openings 3 in communication with each of the hollow extensions 2.

65

When the container C is seated upon a 70 stove the extensions 2 are adapted to be disposed through the holes in the cooking top of the stove whereby it will be perceived that the water or other liquid within the container C will be readily and effectively 75 heated.

75

T denotes a tray having its bottom and side walls provided with a plurality of openings 4. The jars or other receptacles containing the fruit, vegetables or the like 80 to be canned are seated within said tray. The tray T is then positioned within the container C and rested upon the inwardly disposed shoulders 5 carried by the side and end walls of the container C and positioned 85 a predetermined distance above the bottom of the container C.

85

The tray T has its longitudinal and transverse diameters less than the corresponding mean diameters of the container C and in 90 order to maintain the upstanding walls 6 of the tray T spaced relative to the walls of the container C, I provide the vertically disposed strips 7 secured at their upper ends to the walls of the container C and at their 95 lower ends to the shoulders 5 at a point intermediate the ends thereof, whereby each of said strips 7 is disposed on a predetermined incline.

95

In practice the water level within the container C is preferably maintained at three-quarters of an inch above the bottom of the container C as this in practice has been found to produce best results.

100

Carried by the container C and disposed exteriorly thereof is a vertically disposed gage glass G of ordinary construction which has its lower end portion in communication with the interior of the container C. The upper end of the gage is provided with an 110 opening 8 and through said opening is slidably engaged the upstanding stem 9 of

the float 10 mounted in said glass G. The exterior portion of the stem 9 is returned, as indicated at 11, and overlies the gage G and has its lower end provided with the 5 transverse strip 12 preferably red in color which affords a means whereby the water level within the container C may be readily determined.

Secured to an end of the container C is the 10 supplemental container or reservoir R provided at its top with the hinged cover 14 and having its bottom 15 substantially in alignment with the normal water line within the container C. Extending within the 15 supplemental container or reservoir R through the bottom thereof are the extremities of the tube 16 preferably of copper, which tube extends inwardly of the bottom of the container C and underlies the same 20 whereby it will be at once self-evident that the water or other liquid within the supplemental container or reservoir R may be readily and conveniently heated. The tube 16 is held to the bottom of the container C 25 through the medium of the clamping strip 17.

Extending through the supplemental container or reservoir R adjacent the bottom thereof is the pipe 18 in communication with 30 the atmosphere and with the container C. The outer end of the pipe 18 is provided with a valve 19 to afford means whereby an excessive quantity of water or other liquid within the container C may be withdrawn.

35 The pipe 18 is also provided with a port 20 communicating with the interior of the supplemental container or reservoir R and which is under control of the valve 21 extending exteriorly of the supplemental container or reservoir R through the top thereof. By this arrangement it will be at once self-evident that a supply of heated water or 40 other liquid may be readily delivered within the container C as the requirements of 45 practice may necessitate.

The outer face of the supplemental container or reservoir R and the opposite end of the container C are provided with the hand grasps 22 for a purpose which is believed to be clearly apparent to those skilled 50 in the art to which my invention appertains.

From the foregoing description, it is thought to be obvious that a heater constructed in accordance with my invention is of an extremely simple and comparatively 55 inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein 60 shown in carrying out my invention in practice, except as hereinafter claimed.

I claim:

1. A water heater comprising a container, and a second container carried thereby, a 70 discharge pipe in communication with the first named container and extending through the second container and discharging exteriorly of the second container, said pipe being provided with a port in communication with the interior of the second container, a valve adapted to close the port, a controlling valve interposed in the pipe exteriorly of the second container and a tube carried by and underlying the first container 75 and having its extremities in communication with the second container.

2. A water heater comprising a container, and a second container carried thereby, a discharge pipe in communication with the 80 first named container and extending through the second container and discharging exteriorly of the second container, said pipe being provided with a port in communication with the interior of the second container, a valve adapted to close the port, a controlling valve interposed in the pipe exteriorly of the second 85 container, and a tube carried by and underlying the first container and having its extremities in communication with the second 90 container, through the bottom thereof.

In testimony whereof I hereunto affix my signature in the presence of two witnesses.

MARTIN ROBINSON.

Witnesses:

WALTER STOFFEL,
H. F. DUDENBOSTEL.
